I. ZION.

TOY DEVICE.

APPLICATION FILED AUG. 18, 1919.

1,342,577.

Patented June 8, 1920.

Inventor
Isidor Zion,
By his Attorney
Edgar Water & Co.

UNITED STATES PATENT OFFICE.

ISIDOR ZION, OF RIDGEFIELD, NEW JERSEY.

TOY DEVICE.

1,342,577.

Specification of Letters Patent.

Patented June 8, 1920.

Application filed August 18, 1919. Serial No. 318,114.

To all whom it may concern:

Be it known that I, ISIDOR ZION, a citizen of the United States, and residing at Ridgefield, in the county of Bergen and State of New Jersey, have invented certain new and useful Improvements in Toy Devices, of which the following is a specification, such as will enable those skilled in the art to which it appertains to make and use the same.

This invention relates to toy devices, and the object thereof is to provide a device of this class designed to be moved over a floor or other surface and which is provided with movably supported figure members which are actuated by the movement of said toy device, and with this and other objects in view the invention consists in a device of the class specified, which is simple in construction and operation.

The invention is fully disclosed in the following specification, of which the accompanying drawing forms a part, in which the separate parts of my improvement are designated by suitable reference characters in each of the views, and in which:

Fig. 1 is a side view of the complete device;

Fig. 2 a transverse section on the line 2—2 of Fig. 1;

Fig. 3 a bottom plan view of the device;

Fig. 4 a perspective detail view of one of a number of spring supports which I employ and which are shown in use in Figs. 1 and 2 of the drawing; and,

Fig. 5 a section on the line 5—5 of Fig. 4 of a modified form of spring which I employ.

In the drawing I have shown at 10 a box-shaped frame, which is rectangular in form and which opens downwardly. The frame 10 is provided in the top thereof and adjacent to one side wall with an aperture 11 through which a cord or similar member 12 may be passed and secured to the frame 10 at 13 and used for the purpose of pulling the toy device over the floor or other surface.

The frame 10 is mounted on three rollers 14, 15 and 16, the rollers 14 and 15 being rotatably mounted on pins 17 secured to a transverse bearing block 18, which is countersunk or recessed as shown at 19 to receive said roller. The roller 16 is rotatably mounted on a pin 20 secured to depending members 21 on the bottom of the frame 10

and the top of said frame is provided with an aperture 22 through which the roller 16 passes as clearly shown in Fig. 2. The roller 16 is preferably provided with a friction face 23 of rubber or fibrous material.

A small supporting roller 24 is mounted centrally of the block 18, or is rotatably mounted on a pin 25 secured to said block, said roller passing upwardly through an aperture 26 in said block and in the top of said frame as clearly shown in Figs. 2 and 3.

A disk 27 is rotatably mounted in the frame 10 on a central stud 28 which passes downwardly through the top of the frame 10, and said disk is adapted to bear on the top portions of the rollers 16 and 24, the rollers 16 serving to rotate said disk by frictional engagement therewith as the toy device is moved over a floor or surface.

The top of the frame 10 is provided with a plurality of projecting members 29 which are located outwardly of the periphery of said disk, as clearly shown, and connected with the bottom face of said disk are spring attaching devices 30, one of which is shown in detail in Fig. 4. The spring attaching devices 30 are approximately T-shaped in form or consist of an inwardly directed member 31 through which nails, screws, or other devices are adapted to pass for securing said spring to the disk 27, and the cross heads 32 of said attaching devices or the ends thereof are curved upwardly, inwardly and outwardly as shown at 33 to form spring gripping members for a plurality of figure members 34 which are adapted to be detachably connected therewith. The figure members 34 are each provided centrally of the bottom thereof with cam-shaped shoe members 35 which fit within the cross head 32 or curved portions 33 thereof as illustrated in Fig. 1 of the drawing, and these spring members, or the cross heads 32 thereof, are curved to conform with the curvature of the cam-shaped shoe members 35.

It will be apparent that the spring attaching devices 30 in addition to forming tensional means for supporting the figured members 34 also form metallic facings for the cam shoe members 35, which will reduce the friction between said members and the projecting members 29 on the frame 10 as they pass thereover in the manipulation of the device. These spring devices will be so constructed as to permit of the vertical as

well as a slight lateral movement of the members 34.

In Fig. 5 of the drawing I have shown a slight modification in the form of the spring 5 attaching devices 30 in which a side spring member 36 is stamped and bent from the part 31 of the device and another side spring 37 is extended from the cross head 32 and bent upwardly in the manner shown in Fig. 10, and the function of these springs 36 and 37 is to aid in the supporting of the figure members 34 and to prevent the accidental detachment of said members from said devices.

15 It will be readily understood that while I have shown the frame 10 as supported by three rollers, and provided the roller 24 which serves to balance the disk 27, or hold it in a horizontal position, my invention is not limited to this specific arrangement of 20 rollers, and changes in and modifications of the various details of construction herein shown and described may be made, within the scope of the appended claims, without departing from the spirit of my invention or sacrificing its advantages.

Having fully described my invention, what I claim as new and desire to secure by Letters Patent, is:—

30 1. A toy device of the class described comprising a frame having a horizontal top, rollers for supporting said frame to permit of its movement over a surface, a disk rotatably mounted in connection with the top of said frame, means for rotating said disk in the movement of said frame over a surface, figure members movably connected with said disk, and a plurality of projecting members 35 on the top of said frame and in connection with which said figure members are adapted to operate.

2. A toy device of the class described comprising a frame, a disk rotatably mounted in said frame, means for supporting said frame to permit of its movement over a floor surface, means for rotating said disk in the movement of said frame, a plurality of figure members, and spring attaching devices for detachably supporting said members in connection with said disk.

3. A toy device of the class described comprising a frame, a disk rotatably mounted in said frame, means for supporting said frame to permit of its movement over a floor 55 surface, means for rotating said disk in the movement of said frame, a plurality of figure members, tensional means for supporting said members in connection with said disk, and a plurality of projecting

members on said frame outwardly of the periphery of said disk and in connection with which said figure members are adapted to operate.

4. A toy device of the class described comprising a frame, a disk rotatably mounted in said frame, a plurality of rollers connected with said frame to permit of the movement of said frame over a surface, one of said rollers being adapted to operate in connection with said disk to rotate the same in the movement of said frame, another roller for holding said disk in a horizontal position, and a plurality of figure members 65 movably and tensionally supported on said disk.

5. A toy device of the class described comprising a frame, a disk rotatably mounted in said frame, a plurality of rollers connected with said frame to permit of the movement of said frame over a surface, one 70 of said rollers being adapted to operate in connection with said disk to rotate the same in the movement of said frame, another roller for holding said disk in a horizontal position, and a plurality of spring attaching 75 devices connected with and extended beyond the periphery of said disk, a plurality of figure members adapted to be detachably connected with said spring attaching devices and the top of said frame being provided outwardly of the periphery of said disk with a plurality of projecting members 80 in connection with which said figure members are adapted to operate.

6. A device of the class described, comprising a frame, a disk rotatably mounted in said frame, rollers mounted in said frame to permit of the movement thereof over a surface, one of said rollers being adapted to operate in connection with said disk to rotate the same, said frame being provided outwardly of the periphery of said disk with a plurality of spaced projecting members, figure devices provided with cam-shaped shoe members, and spring attaching 90 devices secured to said disk and adapted to be detachably connected with the cam-shaped shoe members of said figure members.

In testimony that I claim the foregoing 95 as my invention I have signed my name in presence of the subscribing witnesses this 14th day of August, 1919.

ISIDOR ZION.
